(57) **CLAIM**

The ornamental design for a pull-out faucet for bath tub, as shown and described.

DESCRIPTION

FIG. 1 is a perspective view showing a new design for a pull-out faucet as positioned on a bath tub, for example, a roman tub or a standard bath tub.

FIG. 2 is another perspective view showing an enlarged view of the pull-out faucet for bath tub in a retracted position.

FIG. 3 is another perspective view showing the pull-out faucet for bath tub in an extended position in which the faucet head is extended via a flexible hose.

FIG. 4 is a front elevational view showing the pull-out faucet for bath tub in the retracted position.

FIG. 5 is another front elevational view showing the pull-out faucet for bath tub in the retracted position and in a different operational state after displacing a water flow control button on the faucet head.

FIG. 6 is a back elevational view of the pull-out faucet for bath tub in the initial retracted position.

FIG. 7 is a left side elevational view thereof.

FIG. 8 is a right side elevational view thereof.

FIG. 9 is a top plan view thereof.

FIG. 10 is another top plan view showing the pull-out faucet for bath tub in the extended position; and,

FIG. 11 is a bottom plan view showing the pull-out faucet for bath tub in the initial retracted position.

The broken lines shown in the drawings illustrate portions of environmental structure and form no part of the claimed design.
